INVENTOR
WILLIAM T. ABBOTT.
BY *Dudley T. Fisher*
ATTORNEY

UNITED STATES PATENT OFFICE.

WILLIAM T. ABBOTT, OF COLUMBUS, OHIO.

PORTABLE DOOR FASTENER.

Application filed January 18, 1922. Serial No. 530,194.

To all whom it may concern:

Be it known that I, WILLIAM T. ABBOTT, a citizen of the United States, residing at Columbus, in the county of Franklin and 5 the State of Ohio, have invented certain new and useful Improvements in Portable Door Fasteners, of which the following is a specification, reference being had therein to the accompanying drawing.

10 My present invention relates to certain new and useful improvements in portable door fasteners, and particularly to that class of door fasteners which are adapted to be carried in the satchel of a traveler and to be 15 applied to the room door in a hotel or lodging house to insure the occupant of the room against intrusion from without.

It is the especial object of this invention to produce a device of the class described 20 which shall be simple of construction, convenient of application, and reliable in operation.

The means by which I attain these objects is fully set forth in the following specification, and illustrated in the accompanying drawing, of which—

Fig. 1 is a sectional view taken through the edge of a door and its jamb, illustrating the relation of my improved door fastener 30 to the door during use.

Fig. 2 is a perspective view of my improved door fastener in assembled relation.

Figs. 3, 4 and 5 are details of the several elements which go to make up the device 35 illustrated in Figs. 1 and 2.

Like numerals refer to similar parts in the several figures.

As illustrated in the drawings my improved door fastener comprises an elongated 40 plate 1 adapted to be inserted between the edge of a door 2 and its jamb 3 when said door is in closed position. Formed on the inner end of the plate 1 is a hook like projection 4 adapted to enter the aperture in the keeper 5 which is commonly supplied to receive the latch bolt of the customary door lock. Formed in the plate 1 and extending longitudinally thereof is a slot 6 through which projects the flange 7 formed along 45 the central longitudinal line of the plate 8 which constitutes a rider adapted to slide longitudinally along one face of the plate 1. The proportions of the parts are such that when the rider plate 8 is in contact with the 50 plate 1, the flange 7 will project to such a distance through the slot 6 that it may be placed

in contact with the face of the door 2, as illustrated in Fig. 1. Means is provided to prevent outward movement of the rider 8 in the wedge 9 which is adapted to engage the 60 flange 7 and a reflexed fold 10 formed at the outer end of the plate 1. When the wedge 9 is in position under the fold 10 its opposite edge enters the notch 11 formed in the outer edge of the flange 7 thereby insuring against 65 accidental withdrawal of the flange 7 from the slot 6.

In operation the plate 1 is placed in position against the door jamb 3 with the projection 4 extending into the aperture of the 70 keeper 5, and the door closed against it. The rider 8 is then placed in position with the flange 7 projecting through the slot 6 and extending towards the door 2. The wedge 9 is then inserted in the notch 11 and under the 75 fold 10, and is moved laterally of the plate 1 until the keeper flange 7 is firmly pressed against the face of the door. When these parts are thus positioned the door 2 will be 80 securely held in closed position, thereby insuring the occupant of the room from intrusion from without.

What I claim as my invention is:—

1. In a device of the class described, the combination with an elongated plate insertable between the edge of a door and its jamb and having a hook at one end adapted to engage said jamb and a reflexed fold at its other end, of a rider slidable longitudinally of the plate and adapted to engage the face of the door, and a wedge adapted to engage said rider and said reflexed fold to prevent movement of said rider relative to said plate as and for the purpose set forth. 85

2. In a device of the class described, the combination with an elongated plate insertable between the edge of a door and its jamb and having a hook at one end adapted to engage said jamb and a reflexed fold at its other end, of a rider slidable longitudinally 90 upon the face of the plate and having a flange adapted to project through a longitudinally extending slot therein to engage the face of the door, and a wedge adapted to engage said flange and said reflexed fold to prevent movement of said rider relative to said plate as and for the purpose set forth. 100

3. In a device of the class described, the combination with an elongated plate insertable between the edge of a door and its jamb, 110 and having a hook at one end adapted to engage said jamb and a reflexed fold at its

other end, of a rider slidable longitudinally along the face of the plate and having a flange adapted to project through a longitudinally extending slot therein to engage the 5 face of the door, and a wedge adapted to engage a notch in said flange to prevent its withdrawal from said slot as and for the purpose set forth.

4. In a device of the class described, the 10 combination with an elongated plate insertable between the edge of a door and its jamb and having a hook at one end adapted to

engage said jamb and a reflexed fold at its other end, of a rider slidable along one face of said plate and having a flange adapted to 15 project through a longitudinally extending slot therein to engage the face of the door, and a wedge adapted to engage said flange and said reflexed fold to prevent movement of said rider relative to said plate as and for 20 the purpose set forth.

In testimony whereof I affix my signature.

WILLIAM T. ABBOTT.
